CLAIM

The ornamental design for a device mount, as shown and described.

DESCRIPTION

FIG. 1 is a top view of a device mount;

FIG. 2 is a front view of the device mount;

FIG. 3 is a right side view of the device mount;

FIG. 4 is a rear view of the device mount;

FIG. 5 is a bottom view of the device mount; and,

FIG. 6 is a rear-right view of the device mount.

The broken lines illustrate unclaimed portions of the device mount and form no part of the claimed design.
